UNITED STATES PATENT OFFICE.

SIDNEY L. PICARD, OF DETROIT, MICHIGAN, ASSIGNOR OF ONE-HALF TO ALFRED P. CHAMBE, OF DETROIT, MICHIGAN.

CARBURETER.

1,238,812.

Specification of Letters Patent. Patented Sept. 4, 1917.

Application filed August 7, 1915. Serial No. 44,218.

To all whom it may concern:

Be it known that I, SIDNEY L. PICARD, a citizen of the United States of America, residing at Detroit, in the county of Wayne and State of Michigan, have invented certain new and useful Improvements in Carbureters, of which the following is a specification, reference being had therein to the accompanying drawings.

10 This invention relates to carbureters for use in connection with explosion engines, and more particularly designed to be used on motor vehicles.

In the construction of carbureters for 15 motor vehicles it is customary to provide means for variably restricting or throttling the inlet of the carbureter to the cylinder of the engine, so as to regulate the force of explosion and the speed of the engine. It is 20 also common with a certain type of carbureters to obtain a variation in the quantity of gasoline introduced into the mixing chamber by the variable suction produced by the operation of the throttle. Thus under ordinary 25 conditions, where the vehicles run upon a level road, the opening of the throttle will cause an increased quantity of gasoline to be drawn into the mixing chamber and absorbed by the large volume of air 30 passing therethrough, while the closing of the throttle will correspondingly diminish the quantity of gasoline and air.

The means of regulation above, while operating satisfactorily under ordinary conditions, have been found to be inadequate under other conditions, for example, when the vehicle is moving slowly under a large load, as where climbing a steep hill the maximum power of the engine is desired, consequently 40 the throttle is wide open. At the same time on account of the slow movement of the piston, the suction produced is not great and frequently results in the failure to introduce sufficient gasoline in the mixing chamber 45 to produce a proper explosive mixture. Thus at a time where the greatest certainty of action is desirable there is the greatest likelihood of failure in explosion.

It is one of the objects of the present invention to obtain a construction in which a sufficient quantity of gasoline will always be drawn in the carbureting chamber, even where the movement of the piston is slow, and this is accomplished by a peculiar construction of automatic regulating valve or

shutter for variably restricting the air conduit or passage contiguous to the gasoline discharge nozzle according to the suction produced by the engine and independent of the regulation of the throttle.

A further object of this invention is to provide a carbureter wherein the parts are constructed with a view of reducing the cost of manufacture and at the same time retain the features by which accuracy, durability, simplicity and ease of assembling are secured, and with such ends in view, my invention resides in the novel construction, combination and arrangement of parts to be hereinafter specifically described and then 65 claimed.

Reference will now be had to the drawing, wherein—

Figure 1 is a vertical sectional view of a carbureter in accordance with my invention, 75 and

Fig. 2 is an elevation of a portion of the same.

In a carbureter which embodies the leading characteristics of my invention, there is 80 necessarily present a float chamber 1 having a gasoline inlet connection 2 from a suitable gasoline supply tank, (not shown). In the float chamber 1 is a needle valve 3, actuated by a float 4 through the medium of pivoted 85 arms 5 engaging a collar 6 on the needle valve 3, said needle valve being capable of use as a priming device. The construction just described is of conventional type and forms no part of my invention. 90

Connected to the float chamber 1 is a base 7 of the carbureter proper, said base having a bridge 8 provided with a port 9 in communication with the float chamber and with a bore 10 to receive a needle valve 11 which 95 is of the ordinary and well known form and adapted to be manually adjusted. At the junction of the bore 10 and the port 9 there is a boss 12 affording a seat for a vertically disposed nozzle 13 having a gasoline outlet 100 orifice or nose 14.

Detachably connected to the lower end of the base 7 is an air inlet elbow 15 having a throttle 16 which controls the passage of air through the elbow 15 and upwardly at 105 the sides of the bridge 8.

Mounted upon the base 7 is the conical lower end of a carbureting chamber 18 having provision at the upper end thereof for attachment to a manifold (not shown). The 110

carbureting chamber 18 has a conventional throttle 19 employed for controlling the supply of fuel to an engine equipped with a carbureter.

5 The base 7 is provided with an annular seat and mounted on said seat around the nozzle 13 is a collar 20. This collar has the outer walls thereof provided with apertured lugs 21 and pivotally connected to said lugs 10 are semi-frusto conical shaped shutters 22. These shutters are in opposed relation and have lateral portions 23 resting normally upon the upper end of the collar 20 and the lugs 21 thereof. The shutters 22 restrict the 15 air passage through the lower end of the carbureting chamber and the upper ends of said shutters are in proximity to the discharge orifice of the nozzle 13. The operation of these shutters is as follows: The discharge orifice of the nozzle 13 being not 20 lower than the level of gasolene in the float chamber, no discharge ensues when the engine is still. If the engine be started its suction will draw fuel through the nozzle 25 13 in proportion to the needs of the engine, and, at the same time the air entering the elbow 15 is directed by the inclined shutters 22 against the end of the nozzle, thus insuring the complete and uniform carbureting of the air. Furthermore, the velocity of the air past the nozzle varies according to 30 the speed of an automobile, thus, when more air is demanded, the shutters automatically open, thus increasing the area of the air inlet passage. It is therefore apparent that 35 the carbureting of the air varies in ratio

to high and low speeds, since at high speeds the air is not sucked past the nozzle at an increased velocity which would decrease the thoroughness of mixing. The shutters 22 40 are simply automatic in their action and constitute a flexible choke which renders the carbureter highly efficient and applicable to any engine.

It is thought that the operation and utility 45 of my improvement will be apparent without further description, and while in the drawing there is illustrated the preferred embodiment of my invention it is to be understood that the structural elements are 50 susceptible to such variations and modifications as fall within the scope of the appended claim.

What I claim is:—

In a carbureter having a base and a gaso- 55 lene discharge nozzle, a collar set in the base and provided with apertured lugs above the base, and opposing frusto-conical shaped shutters pivotally connected to the apertured lugs of said collar and having 60 lateral portions resting normally on the apertured lugs of said collar, said shutters having the upper ends thereof in proximity to the discharge orifice of said nozzle and adapted to automatically restrict the passage around said nozzle.

In testimony whereof I affix my signature in presence of two witnesses.

SIDNEY L. PICARD.
